Primary Examiner — Natasha Vujcic*Assistant Examiner* — Gilbert B Ford(74) *Attorney, Agent, or Firm* — QUARLES & BRADY LLP(57) **CLAIM**

The ornamental design for a medical injector, as shown and described.

DESCRIPTION

FIG. 1 is a front elevational view of an ornamental design for a medical injector;

FIG. 2 is a side elevational view of the medical injector of FIG. 1;

FIG. 3 is a perspective view of a top, front, and right side of the medical injector of FIG. 1; and,

FIG. 4 is a top plan view of the medical injector of FIG. 1. The dash-dash-dash lines illustrate portions of the medical injector that form no part of the claimed design.
